ELECTRIC SWITCH

Filed Feb. 21, 1924

Inventor:
Elmer E. F. Creighton,
by Alexander S. Lunt,
His Attorney.

UNITED STATES PATENT OFFICE.

ELMER E. F. CREIGHTON, OF SCHENECTADY, NEW YORK, ASSIGNOR TO GENERAL ELECTRIC COMPANY, A CORPORATION OF NEW YORK.

ELECTRIC SWITCH.

Application filed February 21, 1924. Serial No. 694,405.

My invention relates to electric switches of the fluid break type and particularly to those which are employed for interrupting circuits of comparatively high voltage.

When the contacts of such a switch are separated beneath the surface of the insulating fluid to open the circuit, the arc drawn immediately volatilizes and dissociates a part of the fluid forming a bubble of highly heated gas extending between the separated contacts. In fluid break switches heretofore constructed it has been customary to confine the contacts and fluid together with the gas generated in a strong receptacle or tank. An object of my invention, however, is to provide an arrangement wherein the gas forming the bubble may find a comparatively free escape and wherein the initial resistance met by the gas bubble is reduced and may be varied, thus reducing the size and pressure of the bubble and hastening the ultimate rupture of the arc.

It is well known that as a bubble increases in size its cooling surface increases less rapidly than its volume, from which it follows that in a bubble of small size the surface is more efficacious in cooling the contents than in a large bubble. According to my invention I provide tubes which extend down through the insulating fluid with their lower open ends adjacent the arc drawn between the switch contacts. The upper ends of the tubes are provided with relief valves and beneath the valves the tubes are connected with a source of gas pressure sufficient to hold the fluid level in the tubes at or near their lower open ends. With this arrangement the gas formed at the contacts may escape up the tubes with comparative freedom, the bubble thereby remaining smaller than it would otherwise with the resultant greater relative cooling effect.

My invention will be better understood by reference to the accompanying specification and drawing and its scope will be pointed out in the appended claims.

Figure 1 is a vertical sectional view of a fluid break switch involving my invention and Fig. 2 is a detail view of the upper end of a relief tube.

Referring to Fig. 1, the tank 1 containing insulating liquid 2 has a lining 3 and a cover 4. In the cover 4 is mounted an insulator bushing 5, through which bushing extends a contact rod 6. Suitable mechanism, not

shown, is provided for lowering and raising the rod 6 into and out of contact with a stationary contact 7. Projecting through and secured to the cover 4 are shown the two tubes 8 of insulating material. The tubes are inclined to bring their lower open ends close to the switch contacts, the adjacent edges of the tubes being preferably cut away as shown. At its upper end each tube is provided with a metallic section 9 which has a number of openings 10 therein and just below these openings is a valve 11, Fig. 2, normally retained upon its seat 12 by a light coil spring 13. Suitable means are shown for adjusting this spring 13 comprising a screw 14 threaded into a cap 15 which may be screwthreaded on the end of the metallic section of the tube. Below the valve seat 12 of each tube a pipe 17 connects therewith, which pipe leads to a reservoir 18 which is filled preferably with a gas free from oxygen. Suitable means obviously may be employed to retain the proper pressure in the reservoir. The pressure of the gas in the reservoir need be only that sufficient to force the liquid level in the tubes 8 down to the desired level and the pressure exerted by the spring 13 should be only sufficient to hold the valves on their seats against this pressure.

When the contacts 6 and 7 are separated to open the circuit the arc drawn between the contacts volatilizes or dissociates a certain amount of the insulating fluid producing a bubble of hot gas. As this gas forming process is exceedingly rapid the gas bubble naturally rapidly increases in size in spite of the inertia of the surrounding liquid. The valve retaining springs 13 being relatively weak and the tubes being substantially full of gas whose inertia as compared with the liquid is negligible, the tubes offer a substantially free path of escape for the gas of the bubble with the result that the gas bubble remains small notwithstanding the rapid generation of gas by the arc. By reason of the small size of the bubble therefore and the resultant greater relative cooling effect of its surface, the arc is more rapidly cooled and more easily extinguished than would be the case were it allowed to expand in the usual manner. An additional advantage lies in the fact that as a result of the free escape of gas through the tubes the tank is relieved of excessive pressure and

the danger of rupture accordingly reduced. It is well known in the case of certain fluid break switches in which pressure of the gas formed by the arc is utilized to assist in extinguishing the arc that it is more difficult to break the arc when interrupting a comparatively small current than when interrupting a heavy current. By varying the pressure supplied by the tank 18 the height 10 of the liquid column in the tubes 8 may be varied to thereby best adapt the switch to meet particular conditions, and because of this differential pressure feature the stationary contact may be covered to a considerable 15 depth by the insulating liquid, yet the mass of liquid which must be displaced to permit the ready escape of the arc gases is relatively small and the specific surface or cooling surface per unit volume of the gas bubbling 20 between the contacts is accordingly larger than would otherwise be the case.

Having thus described one embodiment of my invention I do not wish to be limited to the particular form shown and described 25 as it will be apparent that many modifications therein may be made without departing from the scope of my invention as set forth in the appended claims.

What I claim as new and desire to secure 30 by Letters Patent of the United States, is:

1. An electric switch comprising relatively movable contacts immersed in an insulating liquid and adapted when separated to draw an arc therein, and means for providing 35 a substantially unimpeded path of escape through said liquid for the gas generated by said arc independent of the depth of insulating liquid over said contacts.

2. An electric switch comprising relatively 40 movable contacts immersed in an insulating liquid and adapted to be separated therein, thereby drawing an arc and forming a gas bubble, and means comprising a tubular member providing a substantially 45 unimpeded path of escape through said liquid for the gas of said bubble and means for maintaining the liquid level in the tubular member adjacent the lower end thereof.

3. In an electric switch having cooperating 50 relatively movable contacts immersed in an insulating liquid and adapted when separated to draw an arc therein, means for freely conducting away the gas as it is formed at said arc comprising a tubular member extending from said contacts to the 55 surface of said liquid, and means for main-

taining the liquid in said tube at a level materially lower than that outside of the tube.

4. An electric switch comprising a closed 60 receptacle containing an insulating liquid, relatively movable switch contacts mounted in said receptacle beneath the surface of said liquid and adapted when separated to draw an arc, a tube extending into said receptacle and liquid to a point adjacent said contacts and means for normally maintaining that portion of said tube below the level of said liquid substantially full of gas.

5. An electric switch comprising a closed 70 receptacle containing an insulating liquid, relatively movable switch contacts mounted in said receptacle beneath the surface of said liquid and adapted when separated to draw an arc, a tube substantially full of gas 75 extending into said receptacle and through said liquid to a point adjacent said contacts, the pressure of gas in said tube being sufficient to expel substantially all of the liquid therein, and a resiliently closed valve at the 80 upper end of said tube adapted to retain the gas in said tube normally but to open automatically upon an excess of pressure therein.

6. An electric switch comprising a closed 85 receptacle containing an insulating liquid, relatively movable switch contacts mounted in said receptacle beneath the surface of said liquid and adapted when separated to draw an arc, a tube carried by and extending 90 through the top of said receptacle, the lower open end of said tube being adjacent the arc drawn between said contacts, a spring pressed valve normally closing the upper end of said tube, and a reservoir connected 95 with said tube containing a pressure of a non-inflammable gas sufficient to maintain the insulating liquid substantially displaced from the tube.

7. An electric switch comprising cooperating relatively movable contacts immersed in an insulating liquid and adapted when separated to draw an arc therein forming a gas bubble and means for variably limiting the pressure in said gas bubble at the initial 100 formation thereof, said means comprising a gas filled tubular discharge member having an adjustable spring pressed valve therein.

In witness whereof, I have hereunto set my hand this 19th day of February, 1924.

ELMER E. F. CREIGHTON.
